United States Patent Office

Des. 179,225
Patented Nov. 13, 1956

179,225

RAZOR BLADE DISPENSER

Stanley L. Smith, Stamford, Conn., assignor to Blu Strike
Blade Company, New York, N. Y., a corporation of
New York

Application February 3, 1956, Serial No. 40,035

Term of patent 14 years

(Cl. D58—12)

The figure is a perspective view of a razor blade dispenser showing my new design.

The sides which are not shown are the same as the sides shown.

I claim:

The ornamental design for a razor blade dispenser, as shown and described.
